UNITED STATES PATENT OFFICE.

EDWARD D. BRONSON, OF AMSTERDAM, NEW YORK.

IMPROVEMENT IN BROOM-BAGS.

Specification forming part of Letters Patent No. **136,026**, dated February 18, 1873.

To all whom it may concern:

Be it known that I, EDWARD D. BRONSON, of Amsterdam, in the county of Montgomery and State of New York, have invented a new and valuable Improvement in Broom-Bags; and I do hereby declare that the following is a full, clear, and exact description of the construction and operation of the same, reference being had to the annexed drawing making a part of this specification, and to the letters and figures of reference marked thereon.

The figure of the drawing is a representation of a perspective view of my invention.

This invention has relation to covers for broom-heads; and consists in the hereinafter-described novel construction of a paper bag having an open bottom, by means of which it may be put over the broom-head without ruffling the hurl; also, having flaps or wings at the bottom, which may be closed and fastened when the broom-head is covered, and having its corners covered or partly covered with cloth to prevent the paper from being torn while the broom is being covered.

Broom-covers have heretofore been made in the form of ordinary paper bags, and the broom-head previously compressed by machinery or otherwise inserted through the mouth. This method of covering brooms is, however, tedious, and tends to ruffle up and injure the broom-cover.

My improved cover, being an open-bottom bag or case, may be put down over the broom-handle, and fitted to the head without injuring the latter in the least, and in about one-fourth the time required in covering brooms according to the old method.

In the accompanying drawing, A designates a paper bag or case having four sides and corners, and made either seamless or from a sheet of paper pasted at the edges. The bottom part of the bag is open, so that it may be put over the broom-handle, and thence on the broom-head, and is provided with four wings, a b, produced by cutting the paper upward at the corners. After the bag is put on the broom the wings a are first turned over one upon the other, and the wings b then bent in and fastened together by hook and eye or other equivalent fastening so as to close the bottom of the bag. Finally, the bag is secured to the broom by passing a cord around its neck and tying the same. The wings b are thickened, and made strong to receive the hook and eye c d by folding over the edges and ends, as shown. To prevent the paper from tearing while being applied to the broom, strips of cloth e are pasted over the corners, in the manner indicated in the drawing.

What I claim as my invention is—

The broom-head cover, consisting of the paper bag A having an open bottom, with wings a b folded over and secured by means of hooks and eyes, substantially as specified.

In testimony that I claim the above I have hereunto subscribed my name in the presence of two witnesses.

EDWARD D. BRONSON.
